AUTOMATIC CONTROL MECHANISM

Albert H. Reiber, Chicago, Ill., assignor to Teletype Corporation, Chicago, Ill., a corporation of Delaware

Application April 14, 1933, Serial No. 666,124

8 Claims. (Cl. 178—42)

The present invention pertains to controlling systems and more particularly to controlling methods wherein the medium operated upon controls the action of the operating mechanism.

5 The principal object of this invention is to provide a control device which is readily adjustable to accommodate different conditions of operation.

An important object of the invention is to provide a ready means to interrupt transmission while opportunity is given to the operator to test a line of composition to determine its justifiability before allowing the line thus tested to be transmitted.

10 According to the preferred embodiment of the invention as applied to typographical composition, it is contemplated to control, by means of perforated tape, typesetting telegraphically by insuring that the typographical matter is properly justifiable before it enters the transmitter or tape sensing mechanism at the sending station. Justification, as is commonly known in the typographical art, is the process of making the composed line fill a predetermined length 15 or column width to be set. Briefly, in the typographical art, composing machines of the linecasting type are provided with matrices which consist of small brass units carrying indented characters in their edges and which are of different thicknesses due to the fact that the characters vary in width. Thus, when these matrices are assembled into a line of predetermined 20 definite length, the number of matrices necessary to complete the line varies with the particular matrices used. The length of line, therefore, is dependent not upon the number of characters in the line, but rather upon the thicknesses of the characters or matrices making up the line. Consequently, it is necessary, during the preparation 25 of a perforated tape representing lines of composed matter, to totalize the various thicknesses of matrices corresponding to the code perforations made in the tape, so that the operator will be apprised at all times of the length of line remaining as each key is operated and can thus judge the justifiability of the line.

30 Cooperating with the character matrices and equally determinative of the justifiability of the line, are the justifying matrices, commonly known as expandible spacebands or word spacers which comprise a portion analogous to and having the contour of a character matrix and which is positioned in the line of matrices usually between each series of character matrices comprising a word, and this portion has slidably articulated

thereto and depending therefrom a wedge portion. By means of the wedge portions, the justifying matrices are adjusted between certain ranges of thickness before the casting operation is performed.

5 Therefore, in order to effect the determination of this justification before transmission of typographical matter over a signal wire to a remote station to operate linecasting machines thereat telegraphically, an indicator is provided 10 at the transmitting station which takes cognizance of the expansibility of the spacebands as well as the totalization of the character matrices, and wherein these two functions are performed simultaneously and the net or resultant effect is 15 apparent to the operator at all times who is apprised constantly of the justifiable condition of the line of composition to be set. Such an indicating device may be of the type disclosed in co-pending application Serial No. 613,706, filed May 20 20 26, 1932 by H. L. Krum.

In preparing perforated tape for the remote telegraphic control of typesetting machines wherein the lengths of lines vary according to the column widths of the matter to be composed, it is 25 highly desirable, and even necessary, that the lines of composed matter represented by the perforations in the tape be properly justifiable before they are transmitted, and accordingly the device of the present invention has been provided to afford an adjustable means between the tape transmitter and the keyboard perforator for precluding the transmission of groups of electrical impulses representative of a line of composition not capable of justification. Briefly, this 30 feature is accomplished by an adjustably positionable tape stop lever located between a tape perforator and a tape transmitter, the operative position of which may be adjusted to suit a predetermined minimum effective size of loop of 35 tape between the perforator and the transmitter. The control is effected by the tape becoming taut and acting to raise slightly the tape stop lever to open in turn a pair of contacts in a circuit including the tape stepping magnet of the tape 40 transmitter.

A better understanding of the invention may be had from the following description, taken in conjunction with the accompanying drawing wherein,

50 Fig. 1 is a diagram of a system of remote typesetter control wherein the typesetting mechanism is controlled automatically from a perforated tape which may be prepared telegraphically;

Fig. 3 is a sectional view taken on line 3—3 of Fig. 2;

5 Fig. 4 is a perspective view of the apparatus at a transmitting station, showing the application of the device of the present invention;

Fig. 5 is a fragmentary view of an alternative method of constructing the present device, and

10 Fig. 6 is a cross-sectional view taken on line 6—6 of Fig. 5.

Typesetting by telegraph comprises, fundamentally, a telegraph system and a mechanical type composing apparatus. The latter may be 15 such as is disclosed in U. S. Patents Nos. 436,531 and 436,532 to O. Mergenthaler, dated September 16, 1890, in which circulating matrices are released from magazine channels by operating escapement latches. Such release is made in the 20 order in which the characters are to appear in print, and then assembled in line. The composed line is thereafter transferred to the face of a mold and the mold filled with molten metal, which, when solidified, forms a slug or integral 25 line of type which has received on its edge the impression of the matrices. Thus is produced a slug with type characters thereon. The matrices are thereafter elevated and returned through distributing mechanism to the magazine channels 30 from which they were first released.

The line of type may be composed automatically through the medium of perforated tape prepared telegraphically by the method set forth in copending application Serial No. 600,606, filed 35 March 23, 1932, by H. L. Krum et al., in which the previously mentioned escapement latches are adapted to be selectively operated. This application discloses a permutation code operated device adapted to a modern type-slug casting machine whereby the type-slugs or lines of type may 40 be produced automatically under the control of perforated tape.

A diagrammatical illustration of such a control system is disclosed in Fig. 1. In this figure, 45 the keyboard perforator 11 is of the type shown in aforementioned Krum application, while the transmitter 12 is substantially of the construction disclosed in U. S. Patent No. 1,298,440, dated March 25, 1919, and comprises a tape sensing 50 means and a rotary distributor for imparting the signal impulses successively to the signal line; the reperforator 13 may be of the type shown in U. S. Patent No. 1,884,743, dated October 25, 1932, and the automatically operated slug 55 casting machine 14 may be the combination as disclosed in the aforementioned Mergenthaler patent and the Krum et al. application.

In the system shown in Fig. 1, the typographical matter is prepared upon the keyboard device 60 11 by perforating a tape 15 which is fed to the transmitter 12 by means of which signals are transmitted over the line wire 16 to the receiving station 17. At the receiving station the signals are received by a reperforator 13 by which a tape 65 18 is perforated identical with the original perforated tape 15 at the transmitting station. Tape 18 is then utilized to control the operation of a permutation code operated device such as disclosed in the aforementioned Krum et al. application associated with the typesetting or slug casting machine 14. By this method the typesetting machine at a remote station may be controlled telegraphically and automatically by a distant transmitting station.

70 75 However, as previously noted, it is necessary

in order to insure satisfactory operation of the system that the tape 15 at the transmitting station be properly prepared; that is, that the line of composed matter represented by the series of perforations in the tape be properly justifiable before the information is transmitted. To achieve the production of perforated tape representing justifiable lines of composition, the keyboard counter and perforator 11, such as disclosed in the aforementioned Krum application, 10 is provided with a counting device which cooperates with a scale mechanism which indicates to the operator at all times the justifiable condition of the line being composed. For example, 15 as shown in Fig. 4, the indicating mechanism comprises a sectoral or fan-shaped dial 21, a matrix pointer 22, and a pair of spaceband pointers 23 and 24. The matrix pointer 22 is adapted to move from left to right in response to the operation of the keys 25 to indicate the cumulative widths of characters of which the line is composed. Simultaneously, code combinations 20 of perforations are made in the tape corresponding to the keys depressed.

Each time the space bar 26 is operated, a perforation is produced in the tape. The effect of such a perforation, when reproduced at the distant station, on the composing machine thereat is to insert a spaceband in the line of matrices. The operation of the space bar 26 also causes 30 the spaceband pointers 23 and 24 to be moved differentially, such that the spread of or space between the spaceband pointers, as indicated by dotted lines in Fig. 4, represents the cumulative expansibility of the spacebands. When the 35 matrix pointer 22 moves into the space between the spaceband pointers 23 and 24, as indicated at 27, the operator is apprised of the fact that the line composed and of which a perforated record has been made on the tape 15 is justifiable, and that the end-of-line or elevator signal 40 may now be perforated in the tape, whereupon the elevator key which is one of the group of keys 25 is depressed.

While the operator is thus preparing the tape 45 to correspond to a justifiable line of composed matter, it is desirable that no portion of the matter thus composed shall have been transmitted, because in case it becomes necessary to make a correction therein or other editing to 50 render the line justifiable, the operator shall still have an opportunity to make this change. Also, in the event that the operator should desire to test a line of composition to determine its justifiability, it is contemplated that transmission be 55 arrested until this determination is effected. To insure that this alteration and/or test can still be made and to prevent a non-justifiable line from being transmitted, the device according to the present invention is constructed accord- 60 ingly.

As shown in Fig. 2, the present device comprises essentially a tape stop lever 31, formed at its extremity with a curved portion 32. When the lever 31 is adjusted to the position wherein 65 curved portion 32 is tangent to a horizontal line drawn through pivot 35, the tape 15 will be tangent to the curvature of the portion 32. In this position lever 31, due to the curvature of portion 32, will exert a downward force upon 70 the tape 15 and will prevent any lateral or side motion of the tape, thus serving to guide the tape centrally of the tape guide 33. The tape stop lever 31 comprises a bell crank portion 34 75 pivotally mounted on a stud 35 secured to a

mounting plate 36 affixed to the base of the transmitter 12.

As shown in Fig. 3, the bell crank portion 34 is provided with a spaced portion 37 so as to provide a suitable bearing for the tape stop lever 31 on pivot 35. Tape stop lever 31 is provided with arm 38 of conformation substantially as shown in Fig. 2. The depending arm of bell crank portion 34 coacts with a pair of contacts 39 included in the circuit for the tape stepping magnet 40. This circuit, schematically shown in Fig. 2 extends from source of current or battery 41, over wire 42, through contacts 39 (when closed), over wire 43, thence through contact 44, brush arm 45, and contact 46 of a start-stop transmitting distributor 47, then over wire 48, through winding of stepping magnet 40 to ground. As is well known in the art, the stepping magnet 40 is operated cyclically, once during each revolution of brush arm 45; and also, the inclusion of contacts 39 in the magnet circuit functions to arrest transmission of signals when these contacts are broken. In another form of transmitter 12 the stepping of the tape is performed mechanically by means of a cam fixed to the lower extremity of the distributor shaft 50 and mechanical interconnection between said cam and the tape stepping pawl. In this form of transmitter the contacts 39 control an electromagnet associated with the distributor shaft 50 to govern its cyclic operation, thus for each rotation of shaft 50 the tape will be advanced one step.

Contacts 39 are carried insulatably on an orientation or adjusting lever 51 which is pivotally mounted on the mounting plate 36 and is frictionally pressed thereto by a spring washer 52 inserted between the head of pivot 53 and the lever 51. By this means the lever 51 is frictionally held in any position in which it is placed by the operator. Lever 51 is provided with an extended arm 54 such that it may be readily manipulated. Eccentric screws 55 and 56 are appropriately mounted on the plate 36 to provide adjustable limiting stops for lever 51, such that the automatic control mechanism of the present invention may be oriented or adjusted between the full line and the dotted line position indicated in Fig. 2.

Assuming that the automatic control mechanism has been set in the full line position shown in Fig. 2, the contacts 39 are closed, permitting the stepping magnet to operate and automatic transmission to proceed uninterruptedly. Should any tautness in the tape occur, the tape stop arm 31 would be rotated slightly in a clockwise direction (as viewed in Fig. 2) to open the contacts 39 and thus break the circuit for the stepping magnet and consequently interrupt the transmission. When slack is again provided in the tape, the contacts 39 will again be closed and transmission resumed in the manner which is well known.

Referring again to Fig. 4, the adaptability of the control device of the present invention will be manifest. Should the operator desire to test the line of composed matter represented by the perforations in the tape to determine its justifiability, this can readily be done by means of the present device, in the following manner. Assuming that the automatic control mechanism has been adjusted substantially as shown in the dotted position in Fig. 2, whereby the contacts 39 are closed and portion 32 of tape stop lever 31 is in contact with tape 15 to define a tape

loop of predetermined effective length, and assuming also that it is desired to test the next line of composition to determine its justifiability, the operator will manually swing the lever 51 in a counterclockwise direction approximately to a position represented by the solid line position in Fig. 2. The tape stop lever 31, being held upwardly by the tape, will not follow lever 51 and therefore contacts 39, carried by lever 51, will be swung thereby out of operative engagement with arm 34 of tape stop lever 31 permitting the contacts to open to break the energizing circuit for the stepping magnet 40 to prevent in turn the further feeding of the tape. The operator can now proceed to perforate the line of composition, the justifiability of which is to be tested or determined, and if the line is found to be justifiable; that is, if after the line has been perforated the matrix pointer 22 is located somewhere between the operated spaceband pointers 23 and 24, as at 27, the lever 51 is swung back in a clockwise direction until the contacts 39 are actuated by arm 34 of tape stop lever 31 to close the energizing circuit of the stepping magnet 40. It is manifest from the foregoing that the present invention provides a ready and convenient means to interrupt transmission to give to the operator an opportunity to test a line of composition to determine its justifiability before allowing the line thus tested to be transmitted.

The adjustability of the tape stop arm lends itself advantageously to the preparation of perforated tape for news stories and similar composition. In such instances the tape stop mechanism is adjusted substantially to the position shown in solid lines in Fig. 2 to provide between the units 11 and 12 (Fig. 4) a fairly large effective loop of tape. In this manner several words of perforated matter are stored between the units 11 and 12 preparatory to being transmitted. This procedure permits or enables the operator of the keyboard device to make alterations or changes before transmission. Upon discovering that changes are necessary in the matter stored in the tape the operator back spaces the tape and reperforates rub-out signals (so-called because these signals have no effect on the receiving apparatus such as telegraph printers or operating units for type composing machines) and then proceeds to perforate corrected matter. By this method of procedure the operator is assured that a line of matter prepared is not transmitted immediately but is stored for a predetermined period of time depending upon the effective length of tape in the loop.

Now, upon completion of the perforated record of the news story the advantage of the adjustability of the tape stop mechanism becomes further apparent, as it is not desired to suppress the end of the story but rather to permit its transmission, and to do so with a non-adjustable tape stop mechanism it is necessary for the operator to space out a sufficient amount of blank tape equivalent in length to the length of the loop between units 11 and 12 to ensure the complete transmission of the news story. Ordinarily this would entail the wasting of a considerable amount of line time, as between transmission periods the long loop of tape will consist merely of blank tape. Furthermore, upon resumption of the preparation of perforated tape the first perforation made in the tape by the perforator does not reach the transmitter contacts until the blank tape has been stepped out by the trans-

mitter, thus resulting in a considerable loss of line signalling time.

To obviate all of these detrimental characteristics inherent in the fixed tape stop arrangement the adjustable tape stop mechanism of the present invention is provided, whereby at the completion of a news story the orientation or adjusting lever 51 may be swung upwardly, thus actuating simultaneously tape arm 31 to the position substantially as shown in the dotted position in Fig. 2, so as to provide a minimum effective loop of tape between units 11 and 12, thereby effecting a considerable saving in line signalling time upon the resumption of preparation of perforated tape for the transmission of the next news story, whereupon the tape stop arm 54 will be readjusted to the solid line position (Fig. 2), as previously noted. In this connection it will be noted that when the lever 51 is initially swung downwardly, the lever 31 remains in its upward position, that of resting upon the tape, and the contacts 39 remain open, then as newly perforated tape is prepared the tape loop becomes longer and the lever 31, due to gravity, will follow the tape until subsequently arm 34 of lever 31 contacts with contacts 39 which will again be closed to initiate transmission. Under ordinary conditions, with the arrangement of the units substantially as shown in Fig. 4, a long loop is approximately three times longer than a short loop, thus, from this it is manifest that by employing the device of the present invention the saving in tape material and in line signalling time is substantial.

35

Modification

Figs. 5 and 6 represent a modified form of construction of the tape stop arm. As indicated, the adjusting lever 51 carrying contacts 39 is of like construction as heretofore described. The tape stop arm 61 in this modified form comprises a single piece of wire, or the like, so conformed adjacent to contacts 39 as to provide an abutting portion therefor. The arm 61 is secured to a flanged sleeve 62 carried on stud 63 by means of nut 64 and lock nut 65, as shown in Fig. 6. This construction provides a simple and inexpensive device and one which can be conformed to the proper shape manually.

Having now described in detail certain specific apparatus embodying the present invention, it is, of course, understood that the invention is capable of embodiment in many and varied applications other than that herein disclosed without departure from the spirit and scope of the invention as defined in the appended claims.

What is claimed is:

1. In an automatic control mechanism, an independently rotatable arm responsive to the tension of a tape, means operated directly by said arm for controlling the operation of an associated device, and independently rotatable means on which said means is carried for changing the obliquity of the arm whereby the point at which said arm will be acted upon by said tape is varied.
2. In a tape controlling system, means from which a tape may be advanced, means for advancing the tape, mechanism for controlling said advancing means including an independently ro-

tatable arm operated by the tape, means acted upon directly by said arm to control said advancing means, and independently rotatable means on which said last mentioned means is carried for changing the operative relationship between said last mentioned means and said arm.

3. In an automatic control mechanism, a gravity actuated arm responsive to the tension of a tape between a perforator and a transmitter, a set of control contacts operated by said arm for controlling the operation of the transmitter, and independently rotatable means adapted to co-operate with the gravitational tendency of said arm for changing the obliquity of said arm whereby the point at which said arm will be acted upon by said tape is varied.

4. In combination, a tape perforator, a transmitter, means associated with said perforator for indicating the justifiability of perforated lines of composition, and means located between said perforator and said transmitter comprising a plurality of independently rotatable elements co-operatively associated to control the advancement of the tape, one of said elements responsive to the tension of the tape, the other of said elements adapted to be disassociated from said element to enable the operator to test through the instrumentality of said first recited means a line of composition to determine its justifiability preparatory to effecting its transmission.

5. In a tape controlling system, means from which a tape may be advanced, means for advancing the tape, and means for controlling said advancing means comprising a plurality of independently rotatable elements severally coercive to control the advancement of the tape, one of said elements responsive to the tension of the tape, the other of said elements adapted at will to be disassociated from said element to arrest the advancement of the tape.

6. In an automatic control mechanism, an independently rotatable gravity actuated arm responsive to the tension of a tape, means operated by said arm for controlling the operation of an associated device, and independently rotatable orientation means supporting said first recited means and severally coercive with said arm for determining the locus of operation of said arm.

7. In an automatic control mechanism, a plurality of independently rotatable elements severally coercive to control the advancement of a tape, one of said elements responsive to the tension of the tape, and means operated by said one of said elements for controlling the operation of an associated device, the other of said elements acting as an orientation means for determining the locus of operation of said one of said elements.

8. In a tape controlling system, means from which a tape may be advanced, means for advancing the tape, and means for controlling said advancing means comprising a plurality of independently rotatable elements to control the advancement of the tape, said members being fixedly fulcrumed in cooperative relationship and severally coercive to determine through the adjustment of either of said elements the locus of operation of a predetermined one of said elements.

ALBERT H. REIBER.
